IGNITION DISTRIBUTOR

Karl Schweizer, Stuttgart, Germany, assignor to
Robert Bosch Gesellschaft mit beschränkter
Haftung, Stuttgart, Germany

Application October 28, 1938, Serial No. 237,565
In Germany November 18, 1937

1 Claim. (Cl. 200—19)

In order that high frequency oscillations emitted by the ignition installations in motor vehicles shall cause no disturbances in the supply of news by wireless, the ignition distributors present in the ignition installations are frequently inserted in a metal screening casing.

The screening of ignition distributors according to the present invention is brought about in an especially simple manner by uniting the distributor and the screening casing to form a single constructional part of metal which is sealed by a cover, also of metal.

The present invention is more particularly described with reference to the accompanying drawing which illustrates one form of construction by way of example and in which

Figure 1 is a sectional view, and

Figure 2 is a plan view corresponding thereto.

In the drawing, *a* is a distributor and screening casing consisting of a die casting part, which is sealed by a cover *b* also made from a die casting. The casing *a* and cover *b* are fastened together by two fastening screws (not shown). The distributor shaft *c* is bedded in the metal casing at the part *a'*. The primary current interrupter *d* is accommodated in the lower part of the casing *a*. In addition, it contains a pocket *f* separated from the rest of the casing part by the wall *e*, in which pocket the condenser *g* connected in parallel to the interrupter *d* is inserted.

The condenser *g* is held fast in its operative

position by the strap *h*, which bears on the insulation of the connection terminal *i* placed upon the condenser. The primary current connection is introduced through the sleeve *k*, which is pressed into the casing wall and caulked therein, 5 and connected with the connection terminal *i*. The upper part of the casing *a* is filled by the distributor disc, which consists of two parts *l* and *m* and which is supported on the rim *n* provided in the interior of the casing and is protected here against turning. The ducts *o* serve 10 for the removal of air from the distributor casing. For holding together the parts *l* and *m* and for holding fast the distributor disc, there is only used the plate spring *p*, which is firmly 15 riveted in the cover and which presses on the distributor disc. Through the opening *q* between the casing *a* and the cover *b*, which opening is strengthened by the guide collar *s*, which is firmly held in place by means of the nut *r*, the 20 high tension leads are conducted from the distributor to the sparking plugs.

I declare that what I claim is:

Ignition distributor apparatus comprising a distributor and a screening casing formed as a 25 single integral metallic unit having an internal ring, a metallic cover for sealing said unit, a distributor disc adapted to be supported on said internal rim and a spring carried by said metallic cover for holding said distributor disc on 30 said rim.

KARL SCHWEIZER.
